UNITED STATES PATENT OFFICE.

JAMES A. COMERFORD, OF PHILADELPHIA, PENNSYLVANIA, ASSIGNOR TO GILL GLASS COMPANY, INC., OF PHILADELPHIA, PENNSYLVANIA, A CORPORATION OF NEW YORK.

DESIGN FOR A GLASS LUMINAIRE FOR LIGHTING FIXTURES.

Application filed February 14, 1924. Serial No. 8,635. Term of patent 7 years.

To all whom it may concern:

Be it known that I, JAMES A. COMERFORD, a citizen of the United States, residing at the city of Philadelphia, county of Philadelphia, and State of Pennsylvania, have invented a new, original, and ornamental Design for Glass Luminaire for Lighting Fixtures, of which the following is a specification, reference being had to the accompanying drawing, forming part thereof.

The figure is a perspective view of a glass luminaire for lighting fixture showing my new design.

I claim:

The ornamental design for glass luminaire for lighting fixtures as shown.

JAMES A. COMERFORD.
